ORA A. COLBY, OF IRWIN, AND EARL W. DENMAN, OF SWISSVALE, PENNSYLVANIA,
ASSIGNORS TO WESTINGHOUSE ELECTRIC & MANUFACTURING COMPANY, A COR-
PORATION OF PENNSYLVANIA.

SWITCH MECHANISM.

Application filed December 2, 1920. Serial No. 427,779.

To all whom it may concern:

Be it known that we, ORA A. COLBY, a citizen of the United States, and a resident of Irwin, in the county of Westmoreland and State of Pennsylvania, and EARL W. DENMAN, a citizen of the United States, and a resident of Swissvale, in the county of Allegheny and State of Pennsylvania, have invented a new and useful Improvement in 10 Switch Mechanism, of which the following is a specification.

Our invention relates to switch mechanism and particularly to switch mechanism of the knife-blade type wherein an electric 15 circuit is closed by engagement of a switch-blade member with stationary contact-jaw members.

An object of the invention is to provide a switch mechanism wherein the arcing 20 incident to the opening of the switch is reduced to a minimum or to a point where the arc is not injurious to the blade member or to the contact-jaw members.

Another object is to provide a switch 25 mechanism having the above characteristics wherein the arc-extinguishing member serves as a protective housing for the switch member.

A further object is to provide a switch 30 for the purpose above stated that is efficient and dependable and which is simple and inexpensive to manufacture.

It is well known that the arcs incident to the opening of a switch are frequently destructive to the switch blade and the contact jaws, and to reduce their damaging effects, switches have been so made that they open and close with a snap action, thereby reducing the duration of the arc. However, 40 under certain conditions, the opening of the switch with a snap action does not extinguish the arc before it has had opportunity to fuse or pit the switch blades and the contact-jaw members, and where such pitting occurs the blades and jaw members soon 45 become defective.

The objects above recited and others that will be made apparent throughout the further description of the invention are attained by means of the switch mechanism hereinafter described and illustrated in the accompanying drawings, wherein:—

Fig. 1 is a plan view of an improved

switch mechanism embodying our invention.

Fig. 2 is a longitudinal vertical section on the line II—II of Fig. 1.

Fig. 3 is a longitudinal vertical section on the line III—III of Fig. 1, viewed in the direction of the arrows.

Referring to the drawing, the switch mechanism therein illustrated is of the type used in controlling car-heating systems. The switch is of the rotary snap-action type and is operated by a motor that is preferably controlled by a thermostat. The controlling switch is so connected with the operating motor and the motor is so connected to the terminals of the thermostat (not shown) that, when the temperature of the car or 65 building in which the device is installed exceeds a determined degree, the circuit through the motor is closed by the thermostat and the switch is actuated a quarter turn into a position wherein the circuits 70 through the heating system and through the motor are simultaneously interrupted.

When the temperature of the medium surrounding the thermostat is reduced to a pre-determined degree, the circuit through the 80 motor is again closed by the thermostat and the switch is rotated a quarter turn into a position wherein the circuit through the heater is closed and that through the motor is opened. This system of control is not 85 a part of our invention, and it is believed that a detailed description of its application is not necessary herein.

As shown, the apparatus includes a housing 4 having a bottom casting 5 to which a switch-supporting bracket 6 is secured. The switch mechanism, which is mounted for rotation in this bracket, comprises a rotary shaft 7 to which an insulating hub 8 is secured. This hub carries the switch-blade member 9. The switch blade is rotated by means of an electric motor 10 that is controlled by the above-mentioned thermostat switch (not shown).

The motor is geared to the switch shaft 100 through a train of reduction gearing 11 by means of which the shaft 7 is rotated by the motor at a greatly reduced speed. It will be understood, for the purpose of this description, that the switch is of the snap-action type adapted to be actuated a quarter

turn with a snap action in response to a predetermined rotary movement of the motor.

The features that are new and novel are included in the arrangement of the parts 5 constituting the arc extinguishing mechanism. This apparatus includes an insulating base 12 that is adapted to support the switch terminals or binding posts 13 and the lowermost switch contact-jaw members 14, that are severally supported in recesses 15 located in the underside of the base. These contact-jaw members are connected with their respective terminals 13 by means of any suitable conductors and in any manner desired, depending upon the system of control to which the switch is applied. The base is provided with a circular opening 16, through which the switch hub 8 extends, and the blade member 9 of the switch mechanism is located as close to the upper surface of the base as it is practical to operate it without rubbing the base.

An insulating disc or cap 17 is mounted on the base 12 and entirely encloses the 25 switch member 9, which is free to rotate within the shallow chamber 18, which is provided between the cap and the base. It will be observed that just sufficient space is provided between the opposite sides of 30 the blade member and the walls of the chamber 18 to permit free rotation of the blade. The cap 17 is provided with a series of rectangular openings 19 spaced equidistantly about the axis of the switch and so positioned 35 that the adjacent openings are disposed at right angles to one another. The ends 20 of the openings are countersunk or inclined toward the center thereof and thus form knife edges 21 at the inner edges of the 40 openings, the purpose of which will hereinafter appear.

The base 12 is also provided with a similar series of openings of like formation which register with those in the cap 17; the 45 perforations opening out of, and communicating with, the recess 15 in the base. The relative position is clearly illustrated in Figure 3.

The upper contact-jaw members 22 are 50 connected to their respective lower contact-jaw members 14 by means of the connecting mechanism illustrated in Fig. 3, which comprises a bolt 23 having an enlarged end 24 so tapped as to receive a binding screw 25 55 which connects it with the conductor that leads to, and is connected with, the terminals 13. The contact jaw 14 is mounted upon the shank 27 of the bolt and is disposed between a washer 28 and the enlarged head 24.

60 The bolt 23 is tightly clamped to the base 12 by means of the internally threaded sleeve 29. This sleeve supports the contact-jaw member 22, which is applied to the bolt shank after the cap 17 has been put in place 65 upon the base 12. An oblong washer 30,

which is placed over the contact 22, serves to engage and retain the cap 17. The washer and contact-jaw 22 are retained in position by means of the screw 31.

It will be seen from the foregoing that 70 the switch-blade member 9 turns within the chamber 18 and moves to a position between the yielding contact-jaw members 14 and 22. The snap mechanism (not shown) is adapted to move the blade members a quarter 75 turn with a snap action in response to a predetermined movement of the shaft 7, and to stop the blade member 9 when the ends thereof are in engagement with the contact-jaw members, as illustrated in Fig. 3.

When the blade members move out of engagement with the contact-jaw members, the arc resulting from the separation of the blade member from the jaw members tends to follow the blade and to expand spherically. The knife edges 21 of the insulating base and cap sever that portion of the arc tending to expand spherically from that portion entering the chamber 18 between the base and cap. The arc is thus divided at the entrance edges of the openings 19 into three branches, each of which is exposed to the cooling action of the insulating material of the base and cap, which preferably consists of porcelain.

90 A portion of the arc entering the chamber 18 is so flattened and its surface so extended that it is immediately chilled by contact with the inner walls of the chamber and thus reduced and extinguished. The explosion caused by the arc within the limited confines of the chamber 18 causes the gases of combustion to be violently discharged from the openings 19 at a high velocity, with the result that the arc is blown away from the blade.

100 From actual test it has been found that switches made in accordance with our invention may be operated safely without the least injury to the blades or contact members under loads many times their rated capacity. This feature enables a higher capacity rating to be placed on switch blades and contact-jaws which have heretofore been rated, 110 not as to their current-carrying capacity, but as to their arc resting capacity, for it is well known that the former greatly exceeds the latter.

115 As a result of this construction, switch blades and contact-jaw members may be materially reduced in weight with a corresponding reduction in cost of materials. The durability of the switch is increased because of the absence of a destructive arc.

120 While we have described and illustrated but one embodiment of our invention, it will be apparent to those skilled in the art that various modifications, changes, substitutions, additions and omissions may be made in the 125 apparatus described without departing from 130

the spirit and scope of the invention, as set forth by the appended claims.

We claim as our invention:

1. The combination with co-operating contact members, of an insulating housing enclosing one only of the members and constituting a shallow chamber in which that member operates, the said housing being provided with a gas-escape opening through which the other contact member extends into the chamber.

2. The combination with a stationary contact member and a coacting switch member movable in a predetermined plane, of a housing having closely spaced walls for enclosing the switch member within a shallow chamber in which the switch member operates and having a vent adjacent the contact member, the walls of the chamber being substantially parallel with the plane of movement of the blade and in close proximity to the blade.

3. Switch mechanism comprising a housing having a shallow switch chamber, a movable switch member within the chamber, and contact jaws therefor projecting into the chamber through an opening permitting the escape of gases from the chamber.

4. Switch mechanism comprising a housing having a shallow switch chamber, a movable switch member within the chamber, and contact jaws for the switch member secured to the exterior of the housing and projecting into the said chamber.

5. Switch mechanism comprising a housing having a shallow switch chamber, a movable switch member within the chamber and contact-jaw members for receiving the switch member secured to the housing and projecting into the chamber through countersunk openings in the housing.

6. Switch mechanism comprising a housing having a shallow switch chamber provided with spaced openings, a switch member mounted within the chamber and movable into registry with the said openings, and contact members extending through the openings into engagement with the said switch member.

7. The combination with a contact member and a coacting knife blade member, of a pair of shield members having a space therebetween through which the blade member operates and having the entrance edges thereof so inclined as to form cutting edges on opposite sides of the blade member adjacent the point of engagement of the blade member with the contact member.

8. The combination with a contact member and a coacting switch member, of a housing for enclosing the switch member having openings in the vicinity of the contact member through which compressed gases generated within the housing may escape.

9. The combination with a contact mem-

ber and a coacting switch member, of a housing for the switch member comprising a heat-absorbing body provided with a shallow chamber in which the switch member operates and having a vent adjacent the contact member, the inner walls of the chamber on opposite sides of the switch member being disposed in close proximity to the switch member and adapted to permit the escape of gases only through the said vent whereby arcs incident to the opening of the switch are directed toward the said vent and cooled by the said walls.

10. Switch mechanism comprising an insulating base, a contact member, a rotatable shaft member, a switch member mounted on the shaft member adjacent one face of the base and for rotary movement into and out of engagement with the contact member in a plane parallel to the adjacent face of the base, and an insulating cover for the switch member closely fitting about the shaft member and co-operating with the base to form a shallow chamber therebetween in which the switch member operates, whereby arcs incident to the opening of the switch member are confined and chilled.

11. Switch mechanism comprising a pair of insulating plates having a shallow annular chamber therebetween, contact-jaw members disposed on the outer faces of the plates and extending into the chamber through perforations therein, and a switch member within the chamber movable into and out of engagement with the contact-jaw members.

12. Switch mechanism comprising a contact member, a rotatable switch member movable into and out of engagement with the contact member, a shaft member for supporting the switch member, and a pair of heat-absorbing plates closely fitting about the shaft member and having their adjacent faces disposed in close proximity to the switch blade and on opposite sides thereof whereby the arc incident to the opening of the switch member is confined between the plates and chilled.

13. The combination with a stationary contact member and a coacting switch member movable in a predetermined plane, of a housing for enclosing the switch member comprising a pair of insulating plates constituting a shallow chamber in which the switch member operates and is retained in assembled relation by the contact member, the walls of the chamber being substantially parallel with the plane of movement of the blade and in close proximity to the blade.

In testimony whereof, we have hereunto subscribed our names this 30th day of November, 1920.

ORA A. COLBY.
EARL W. DENMAN.
